UNITED STATES PATENT OFFICE.

JOHN RESTEIN, OF PHILADELPHIA, PENNSYLVANIA, ASSIGNOR TO
RESTEIN BROTHERS, OF SAME PLACE.

IMPROVEMENT IN MUSICAL MERCHANDISE-BOXES.

Specification forming part of Letters Patent No. 159,218, dated January 26, 1875; application filed
November 16, 1874.

To all whom it may concern:

Be it known that I, JOHN RESTEIN, of the city and county of Philadelphia and State of Pennsylvania, have invented a new and useful Improvement in Musical Merchandise-Boxes; and I do hereby declare the following to be a clear and exact description of the nature thereof, sufficient to enable others skilled in the art to which my invention appertains to fully understand, make, and use the same, reference being had to the accompanying drawings making part of this specification, in which —

Figures 1 and 2 are central vertical sections of the device embodying my invention. Figs. 3 and 4 are bottom views thereof.

Similar letters of reference indicate corresponding parts in the several figures.

My invention consists in the combination with a box for purposes of packing and merchandise generally, of a musical or other sounding instrument, which shall be operated by the actions of opening and closing the box.

Referring to the drawings, A represents a box constructed of a lid and body which fit each other telescopically and closely, as is well known in the class of collar-boxes. The bottom of the body or the lid or other portion of the box will be cut away or formed with an opening which will be occupied by a reed,

whistle, or other wind, musical, or sounding apparatus, B, which is to be firmly secured in position. It will be seen that when the box is opened the current of air drawn therein will pass through the apparatus B and sound or play the same. In closing the box, the air will be expelled through the apparatus B, and the same result is accomplished as on opening the box. This feature is attractive and will serve to direct attention to the class of goods packed in the box, thus rendering them more saleable.

When the box is emptied, it may be handed to children as an accordion, whistle, or musical instrument, and designed to amuse them will render serviceable an article that is most generally thrown away or destroyed.

Having thus described my invention, what I claim as new, and desire to secure by Letters Patent, is —

A collar or other box, provided with a closely-fitting cover, made to slide telescopically therewith, and having a reed or whistle arranged to be sounded by opening or closing the box, substantially as and for the purpose specified.

JOHN RESTEIN.
